UNITED STATES PATENT OFFICE.

RICHARD MOONEY, OF HENRYETTA, OKLAHOMA.

DOOR CONSTRUCTION.

Application filed November 15, 1924. Serial No. 750,209.

To all whom it may concern:

Be it known that I, RICHARD MOONEY, a citizen of the United States, residing at Henryetta, in the county of Okmulgee and State of Oklahoma, have invented certain new and useful Improvements in Door Constructions, of which the following is a specification.

This invention relates to door constructions, and more particularly to a garage door construction.

An object of the invention is the provision of a door construction consisting of double doors, that is relatively simple and durable.

15 A further object of the invention is the provision of means for locking the doors of a garage or similar building in opened or closed position.

A still further object of the invention is 20 the provision of means for operating the latching mechanism.

In the accompanying drawings, I have shown one embodiment of the invention. In this showing:

25 Figure 1 is a front elevation of the doors looking from the interior of the building,

Figure 2 is a horizontal sectional view on line 2—2 of Figure 1,

Figure 3 is a similar view on line 3—3 of 30 Figure 1,

Figure 4 is a vertical sectional view,

Figure 5 is a detail view of the latch and latch operating mechanism, and

Figure 6 is a detail sectional view on line 35 6—6 of Figure 1.

In constructing the door, I provide a frame adapted to fit the opening in the building and consisting of vertical end members 1 spaced from each other a distance 40 equal to the width of the double doors. These members may be formed of channel iron or the like and are provided with front and rear flanges 2 and 3. The lower ends of the end members are adapted to be 45 received in a body of concrete 4 to rigidly support them. As shown, the frame of the door is assembled before being placed in position and the end members connected by a lower member 5. At the top, the end members 50 are connected by a transverse member 6. After the frame has been constructed, a ditch is formed across the door-way or opening in the building, and the frame placed in position. The mixed concrete is then 55 placed in the ditch and permitted to harden. The rear end of the frame is provided with

vertical members 7, slightly spaced from the end members and substantially in alignment with these vertical members, there is provided a pair of posts or bearings 8 arranged 60 adjacent the front of the frame. Doors 9 are mounted on these posts and rotate about them as pivots. As shown, plates 10 are connected to the rear sides of the door and these plates carry sleeves 11 which are adapted 65 to receive the posts. The lower portion of each post is enlarged, as at 12 (see Figure 4) to substantially the same diameter as the sleeve and above the top of the sleeve, the post is surrounded by a spacing member 13. 70 The end members 1 and the vertical members 7 are adapted to support horizontally arranged plates 14 which are provided with curved inner edges 15. These plates are provided with openings 16 and 17, adjacent 75 their front and rear edges. As shown, the edge of each door is provided with a slot 18 adapted to receive the plates 14 when the doors rotate on their pivots. One of the doors is provided with a projecting strip 80 19 at its inner edge adapted to be engaged by the inner edge of the opposite door when the doors are in closed position (see Figure 2).

The door is provided with suitable latching mechanism adapted to engage the openings 16 and 17 and retain it in the full line closed position or in the dotted line open position shown in Figure 2 of the drawings. As shown, a lever 20 is pivotally 85 mounted on a pin 21 and arranged on the inner side of the door. This lever extends substantially the entire width of the door and is adapted to oscillate within a guide 22. A link 23 is secured to one end of the lever. 95 A pin 24 is arranged in the door and the projecting portion thereof is provided with suitable operating handles 25. This pin carries a pair of cranks 26 adapted to be connected to the lower end of the link 23. The 100 opposite end of the pivoted lever 20 is connected to a latch pin 27 by means of an eyebolt 28. As shown, the latch pin passes through a pair of sleeves or guides 29 arranged on the interior of the door. Adjacent the lower guide, the latch pin is provided with an enlargement 30 and a coil spring 31 surrounds the latch pin. The lower end of the coil spring engages the enlargement 30 and the upper end engages the 105 upper collar 29 whereby the latch pin is normally projected and is adapted to enter

one of the openings 16 or 17. Coil springs 32 are secured to the inner face of the door and to the vertical members 7 and are adapted to normally retain the doors in closed position. The front of one of the doors 5 may be provided with the usual staple 33, adapted to receive a hasp 34 carried by the other door section and a padlock 35 may be arranged in the staple to lock the doors in 10 closed position.

Additional means may be provided for retaining one of the doors in closed position. As shown, locking rods 36 may be secured to eye-bolts 37 mounted in the 15 vertical member 7 and these rods are provided with depending ends 38 adapted to be received in openings formed in braces 39 on the rear face of the door.

The operation of the device will be 20 apparent from the foregoing description. After the padlock 35 has been removed, the door section to the right in Figure 1 of the drawings, may be opened by turning the knob to raise the latch pin 27 from the 25 opening 16. The door is then swung to a substantially quarter revolution and the pin enters the opening 17 to retain the door in the open position shown in dotted lines in Figure 2 of the drawings. This prevents 30 the door from blowing closed while the automobile is being driven from the garage. The rods 36 are then released from the other door and it is opened in the same manner. The doors are thus retained in 35 opened position when desired and as soon as the latch pins are released from the openings 17, the springs move the doors to their closed position.

It is to be understood that the form of 40 my invention herewith shown and described is to be taken as a preferred example of the same, and that various changes in the shape, size, and arrangement of parts may be resorted to without departing from the 45 spirit of the invention or the scope of the subjoined claims.

I claim.

1. A device of the character described 50 comprising a door frame, a door pivoted at a point spaced from one edge thereof to said frame, the opposite edge of said door being adapted to swing toward and away from said frame, a lever pivoted intermediate its ends to said door, one end of said 55 lever being arranged adjacent the first named edge of said door, a latch arranged adjacent the first named edge of said door and connected to the adjacent end of said lever to be operated thereby, and a latch plate carried by said frame, said plate being 60 provided with an opening to receive said latch.

2. A device of the character described 65 comprising a hollow door frame, a pivot pin arranged adjacent one edge of said door

frame, a door connected to said pivot pin, one edge of said door projecting outwardly from said frame, the opposite edge of said door extending beyond said pivot pin into said frame, a latch plate mounted within 70 said frame adjacent the last named edge of said door, and a latch carried by the last named edge of said door and adapted to engage said latch plate.

3. A device of the character described 75 comprising a hollow door frame including side walls, a portion of one side of said frame being open, a pivot pin adjacent one edge of said frame in the open side thereof, a door connected to said pivot pin, one 80 edge of said door projecting outwardly from said frame, the opposite edge of said door extending beyond said pivot pin into said frame, a latch plate arranged in said frame and secured to the walls thereof, said latch 85 plate being provided with openings arranged concentric with said pivot pin, and a latch carried by said last named edge of said door and adapted to engage within the openings in said latch plate. 90

4. A device constructed in accordance 95 with claim 3 provided with a lever mounted against one face of said door and pivotally connected intermediate its ends thereto, one end of said lever being arranged adjacent the outwardly projecting end of said door, the other end of said lever projecting beyond said pivot pin to a point adjacent the opposite end of said door and being connected to said latch. 100

5. A device of the character described comprising a door frame including a plurality of side walls arranged substantially in rectangular form, two of the adjacent walls of said frame terminating at points 105 spaced from one corner of said frame to provide an open corner portion, a pivot pin arranged adjacent the open corner portion of said frame, a door connected to said pivot pin, one edge of said door projecting 110 outwardly beyond said frame, the opposite edge of said door extending beyond said pivot pin into said frame and contacting with one wall of said frame when said door is in one position, a latch plate mounted 115 within said frame adjacent the last named edge of said door and secured to the walls of said frame, said latch plate having one edge curved and arranged concentric with said pivot pin, the last named edge of said door being provided with a slot into which said plate projects, said plate being provided with openings arranged concentric with said pivot pin, and a latch carried by the last named edge of said door and adapted 120 to engage within said openings. 125

In testimony whereof, I affix my signature.

RICHARD MOONEY.
